HARRY E. DOERR, OF ST. LOUIS, MISSOURI, ASSIGNOR TO SCULLIN STEEL CO., OF ST. LOUIS, MISSOURI, A CORPORATION OF MISSOURI.

DRAFT MECHANISM.

1,353,224.

Specification of Letters Patent. Patented Sept. 21, 1920.

Application filed March 31, 1919. Serial No. 286,273.

To all whom it may concern:

Be it known that I, HARRY E. DOERR, a citizen of the United States, residing at St. Louis, in the county of St. Louis and State 5 of Missouri, have invented certain new and useful Improvements in Draft Mechanism, of which the following is a specification.

This invention relates to draft mechanism.

In most draft arm constructions used now- 10 adays there is an offset at the body bolster, the draft arms running straight from the front end of the car back to the body bolster and then inclining upwardly and over the bolster, the arms usually being secured to 15 either the sides or bottoms of the sills. This type of draft arm has the disadvantage of transferring the impact of the blow on the coupler through the draft arm to the top member or portion of the body bolster. This 20 should be obviated.

Accordingly, one object of my invention is to overcome this and other disadvantages and to provide a simple, durable and compact draft mechanism wherein the draft 25 arms and the body bolster are connected in an improved manner to meet all the requirements under service conditions.

This and other objects are accomplished by means of the mechanism shown on the ac- 30 companying sheets of drawings, in which—

Figure 1 is a plan view of draft mecha- nism embodying my invention;

Fig. 2 is a fragmentary longitudinal sec- 35 tional view of the same arrangement, the draft arms being shown in full lines and the body bolster and connecting parts shown in dot and dash lines;

Fig. 3 is a fragmentary end view of the draft arms showing their association with 40 the body bolster and means for connecting said parts together; and

Fig. 4 is a sectional view taken in the plane of line 4—4 of Fig. 1.

The various novel features of my inven- 45 tion will be apparent from the following de- scription and drawings and will be partic- larly pointed out in the appended claims.

Referring to the figures of the drawings, it will be noted that I have shown the draft 50 arms 10, preferably made integral of cast steel, provided with pocket portions 11 on the inner sides of said arms between an end sill 12 and an integrally formed body bolster 13 for receiving the followers of the 55 draft gear. The draft arms 10, instead of extending back to the body bolster and then

inclining upwardly and passing over the same, are reduced vertically at the body bolster in order that the draft arms may pass in a straight line through and extend beyond 60 said bolster. These draft arms 10 prefer- ably pass through spaced openings 14 in the body bolster 13 and are secured to adjacent vertical flanges 15 of the body bolster by rivets 15' which may pass through holes 16 65 in said flanges. Not only are the draft arms 10 secured to the body bolster at the flanges 15, but they are also rigidly connected to the body bolster by gusset plates 17 at the rear of the body bolster and gusset plates 18 in 70 front of the body bolster. These gusset plates connect the upper and lower flanges 25 and 26 of the draft arm to the upper and lower flanges 19 and 20 of the body bolster, said parts being secured together by 75 suitable rivets 24. These draft arms are se- cured beneath the center sills 21 of the car which overlie the body bolster. A reinforce- 80 ing plate 22 also is interposed between the upper surface of the reduced rear portion of the draft arm and the overlying portion of the car center sills, said plate 22 being secured to the draft arms and body bolster by suitable rivets 23.

By means of this construction the impact 85 of the blow on the coupler is not transferred through the draft arms to the top of the body bolster, but properly distributed throughout the depth of the bolster. Fur- 90 thermore, the construction is simple, com- pact and rigid, and adapted to meet all the requirements under service conditions.

It is my intention to cover all modifica- 95 tions of the invention falling within the spirit and scope of the following claims.

I claim:

1. In draft mechanism, the combination of a bolster having openings therein, integrally formed draft arms extending through the said openings and being secured to said bolster, and gusset members connecting said draft arms and bolster.

2. In draft mechanism, the combination of a bolster having openings therein, integrally formed draft arms extending through the said openings and being secured to said bolster, said bolster and draft arms having flanges, and gusset plates secured to the flanges of said arms and bolster.

3. In draft mechanism, the combination 110 of a body bolster having openings therein and adjacent flanges, single piece draft arms

extending through said openings and being secured to said flanges, and gusset plates connecting said draft arms with said bolster.

4. In draft mechanism, the combination 5 of a body bolster having openings therein and associated vertical flanges, said bolster also having upper and lower laterally extending flanges, draft arms extending through said openings and being secured to 10 said vertical flanges, said draft arms having upper and lower laterally extending flanges, and gusset plates connecting the upper and lower flanges respectively of said draft arms and bolster.

5. In draft mechanism, the combination 15 of an integrally formed bolster having an opening therein, an integrally formed draft arm having a reduced portion extending through said opening and being secured to said body bolster, gusset members connect- 20 ing said draft arm and bolster, and a reinforcing plate secured to the draft arm and bolster at the reduced portion of the draft arm.

Signed at St. Louis, Missouri, this 24th day of March, 1919.

HARRY E. DOERR.
